SEAR-MECHANISM FOR FIREARMS

Albert F. Laudensack, New Haven, Conn., assignor to Winchester Repeating Arms Company, New Haven, Conn., a corporation of Maryland

Application July 31, 1935, Serial No. 33,957

16 Claims. (CL 42—69)

This invention relates to an improvement in firearms and relates in particular to sear-mechanisms therefor.

One of the objects of the present invention is to provide a sear-mechanism for firearms which is characterized by superior reliability.

Another object is to provide a superior sear-mechanism especially adapted for up-turn-and-pullback bolt-action firearms.

A further object is to produce a superior sear-mechanism for firearms which will provide for a substantially-uniform trigger-pull.

A still further object is to provide a bolt-action firearm in which uniformity of trigger-pull is assured, despite variations in the speed at which the bolt thereof is closed.

With the above and other objects in view, as will appear to those skilled in the art from the following, considered in conjunction with the accompanying drawings and appended claims, the present invention includes all features disclosed herein which are novel over the prior art.

In the accompanying drawings:

Fig. 1 is a broken view in side elevation of an upturn-and-pullback bolt-action firearm embodying the present invention, with the stock and associated parts omitted;

Fig. 2 is an under-side view thereof;

Fig. 3 is a vertical central-longitudinal sectional view thereof, with the parts shown in the positions which they assume when the firearm is cocked;

Fig. 4 is a transverse sectional view taken on line 4—4 of Fig. 3;

Fig. 5 is a view similar to Fig. 3, but showing the parts in the positions which they assume immediately after the firearm is fired;

Fig. 6 is a similar view, but showing the parts in the positions which they assume after the firearm has been fired and the bolt-operating handle has been upturned, preparatory to the retraction of the bolt;

Fig. 7 is a transverse sectional view taken on line 7—7 of Fig. 6;

Fig. 8 is a perspective view of the sear; and Fig. 9 is a perspective view of the bolt-operating handle.

The particular firearm herein chosen for the illustration of the present invention is of the so-called "upturn-and-pullback bolt-action" type, and includes a receiver 20 of substantially-tubular form having a transverse dovetail sight-receiving groove 21 in its upper rear portion and having threaded into its forward end the rear end of a barrel 22 having a cartridge-chamber 23

therein. The receiver 20 is also provided with an axial bolt-receiving passage 24, the forward upper portion of which is intersected by a loading-and-ejection opening 25.

Mounted in the bolt-receiving passage 24 of the receiver 20, with capacity for reciprocation therein, is a cylindrical bolt 26 having an axial firing-pin passage 27 therein intersected at its forward end by a relatively-small eccentric passage 28. Projectable through the said passage 28 is the firing-point 29 of a firing-plunger 30 mounted in the passage 27 in the bolt 26.

The rear portion of the firing-plunger 30 is of tubular form in cross-section and provides a firing-spring chamber 31 receiving a firing-spring 32, which latter thrusts at its forward end against the front wall 33 of the firing-spring chamber 31. The rear end of the firing-spring 32 is seated against a pin 34 mounted in and extending transversely through the reduced cylindrical rear portion 35 of the bolt 26. The said pin extends through longitudinal clearance-slots 36—36 respectively formed in the rear portion of the top and bottom walls of the firing-plunger 30 so that the said firing-plunger may reciprocate independently of the bolt 26 but, at the same time, be prevented from relative rotary movement with respect thereto.

As shown, the rear end of the firing-plunger 30 may be provided with a head 37 having forwardly-extending nibs 38—38 adapted to enter complementary notches 39—39 in the rear edge of a bolt-operating sleeve 40 which is mounted with capacity for turning movement upon the reduced cylindrical rear portion 35 of the bolt 26 and provided with an integral laterally-offsetting handle 41 terminating in a ball-grip 42.

Intermediate its respective opposite ends, the under-portion of the firing-plunger 30 is transversely cut away to provide a substantially-vertical forwardly-facing cocking-shoulder 43 adapted to be engaged, when the firearm is cocked, by the rear face 44 of a sear-nose 45 vertically upstanding from a pivotal sear 46. The said sear is pivotally mounted adjacent its forward end by means of a transverse pivot-pin 47, in a vertically-extending passage 48 formed in the under side of the receiver 20. The said sear-nose 45 of the sear 46 projects upwardly for the engagement of its rear face 44 with the cocking-shoulder 43, through a longitudinal clearance-slot 49 formed in the under side of the bolt 26.

The portion of the sear 46 which is located forwardly of the pin 47 is provided with an upwardly-opening spring-pocket 50 receiving a sear-spring 55

51 bearing at its upper end against the under surface of the receiver 20 and exerting a constant effort to swing the said sear in a clockwise direction to lift its sear-nose 45. The sear 46 is also 5 formed with a vertical passage 52 receiving the upper end 53 of a trigger 54 and is provided just to the rear of the said passage 52 with a downwardly-facing trigger-engaging shoulder 55 adapted to rest, when the firearm is cocked, upon 10 an upwardly-facing sear-engaging shoulder 56 formed upon the trigger 54 before referred to.

To limit the degree of overlap of the trigger-engaging shoulder 55 and the sear-engaging shoulder 56, the upper portion of the said trigger 15 54 is provided with an inclined adjusting-screw 57, the rear terminal of which is engageable with the rear wall 58 of the passage 52 in the sear 46 for the purpose just referred to.

The rear portion of the sear 46 is formed with 20 an upwardly-opening pocket 59 receiving a sear-actuating plunger 60 having a stem 61 downwardly-extending through a bearing-passage 62 opening downwardly through the sear 46 from the lower end of the said pocket 59 therein. The 25 stem 61 of the sear-actuating plunger 60 is encircled by a sear-actuating spring 63 housed in the pocket 59 of the sear 46 and exerting a constant effort to move the plunger 60 upwardly with respect to the sear 46, and hence tending, under 30 certain conditions as will hereinafter appear, to depress the rear end of the said sear.

The upper terminal of the sear-actuating plunger 60 is adapted to engage, when the bolt 26 is in its closed position, with a detent-notch 64 35 formed in the bolt-operating sleeve 40 before referred to, as shown in Figs. 3 and 4 of the drawings. The upper end of the said plunger 60 is also adapted, when the bolt-operating handle is in its elevated position, as indicated in Figs. 6 40 and 7, to engage with a cam-surface 65 also formed upon the exterior surface of the bolt-operating sleeve 40. Under the conditions just described, the upward movement of the sear-actuating plunger 60 with respect to the sear 46 is 45 limited by a stop-pin 66 extending transversely through the stem 61 of the said plunger and engageable for the purpose described with the under face of the adjacent portion of the sear 46, as illustrated in Fig. 6.

50 The trigger 54 before described is pivoted intermediate its upper end 53 and its finger-piece 67 by means of a pivot-pin 68 extending transversely thereof and mounted at its respective opposite ends in complementary fingers 69—69 depending from a trigger-bracket 70. The said trigger-bracket is of substantially U-shaped form in horizontal section, as indicated in Fig. 2, and has its respective opposite side walls 71—71, from which the fingers 69—69 depend, attached to the 55 receiver 20 by means of the pin 47 upon which the sear 46 swings.

The rear wall 72 of the trigger-bracket 70 is bent to provide two rearwardly-extending ears 73 and 74. The ear 73 just referred to has extending through it a screw 75 threaded into the under wall of the receiver 20 and serving to secure the rear end of the said trigger-bracket in place. The ear 74 just referred to of the trigger-bracket 70 mounts an internally-threaded bushing 76 receiving an adjusting-screw 77, the lower end of which engages the upper end of a trigger-spring 78, which latter has its lower end seated in a pocket 79 formed in the upper rear face of the finger-piece 67 of the trigger 54.

75 For the purpose of a better understanding of

the operation of the mechanism above described let it be presumed that the parts are in the positions in which they are indicated in Fig. 3. In the figure referred to, it will be noted that the breech-bolt is in its fully-closed-and-locked position and that the upper end of the sear-actuating plunger 60 is entered into the detent-notch 64 in the bolt-operating sleeve 40, thereby placing the sear-actuating spring 63 under tension which tends to depress the rear end of the sear 46. The depression of the rear end of the said sear is prevented at this time, however, by the resting of the trigger-engaging shoulder 55 of the said sear upon the sear-engaging shoulder 56 of the trigger 54.

If, now, the trigger 54 be operated by means of its finger-piece 67 to move its sear-engaging shoulder 56 forwardly from under the trigger-engaging shoulder 55 of the sear 46, the sear-actuating springs 63 will assert itself and swing the rear end of the said sear downwardly to withdraw the sear-nose 45 of the latter out of the path of the cocking-shoulder 43 of the firing-plunger 30. The said firing-plunger will thus be permitted to snap forwardly under the urge of its firing-spring 32 to impinge its firing-point 29 against the rim of a cartridge located in the cartridge-chamber 23 of the barrel 22.

The movement of the seal 46 above described is effected by the sear-actuating spring 63 against the resistance of the sear-spring 51, owing to the location of the former spring at a greater distance from the transverse pin 47 than is the latter spring 51. It may be noted that when the sear-actuated spring 63 acts to downwardly swing the rear end of the sear 46, as above described, there will be very slight retraction of the firing-pin until such time as the upper rear corner of the sear-nose 45 clears the lower forward corner of the cocking-shoulder 43 of the said firing-pin.

The parts will now have assumed the positions in which they are indicated in Fig. 5.

The firearm having been fired, the next normal step in the use thereof would be to swing the bolt-handle 41 upwardly from the position in which it is shown in Fig. 4 into the position in which it is shown in Fig. 7, thereby turning the bolt-operating sleeve 40 into position to bring its cam-surface 65 into registration with the upper end of the sear-actuating plunger 60, thus permitting the said plunger to move upwardly with reference to the sear 46 under the urge of the sear-actuating spring 63 until the stop-pin 66 of the said plunger engages the under face of the adjacent portion of the sear 46.

The engagement of the stop-pin 66 with the sear 46 as just above described serves to relieve the rear end of the said sear from any further downward urge by the spring 63 and, owing to the clearance provided by the cam-surface 65 and the clearance-slot 49 in the bolt 26, the trigger-engaging shoulder of the said sear will be permitted to be raised by the sear-spring 51 to a point slightly above the sear-engaging shoulder 56 of the trigger 54, whereupon the said trigger will swing in a counterclockwise direction as viewed in the drawings, to again interpose its shoulder 56 in the path of downward movement of the shoulder 55 of the sear 46.

The parts will now have assumed the positions in which they are shown in Fig. 6.

The bolt 26 may now be moved axially rearwardly by its now-upturned handle 41 to effect the extraction and ejection of the fired cartridge. After the bolt 26 has been moved to the limit of

its normal rearward travel, it may then be moved forwardly by means of its handle 41 to engage the cocking-shoulder 43 of the firing-plunger 30 with the rear face 44 of the sear-nose 45. The further forward travel of the bolt will compress the firing-spring 32 and ultimately bring the cam-surface 65 of the bolt-operating sleeve 40 into position for engagement with the upper end of the sear-actuating plunger 60.

10 Now when the handle 41 of the bolt-operating sleeve 40 is swung downwardly into its normal position, in which its rear surface engages with a locking-abutment 80 in the side wall of the receiver 20, the cam-surface 65 of the said bolt-operating sleeve 40 will act to fully depress the sear-actuating plunger 60, thus tensioning the sear-actuating spring 63. The said spring 63 will, when so tensioned, swing the rear portion of the sear 46 slightly downwardly until such movement 15 is checked by the engagement of the shoulder 55 of the said sear with the shoulder 56 of the trigger 54.

15 The parts will now have reassumed the positions in which they are shown in Fig. 3, in which figure, it will be observed, the sear-engaging shoulder 56 of the trigger 54 extends rearwardly beneath the trigger-engaging shoulder 55 of the sear 46 and thus prevents the sear-actuating spring 63 from depressing the rear portion of the 20 said sear until such time as the trigger is again pulled.

25 By means of the foregoing construction, a firearm is provided in which the trigger-pull required to effect the release of the firing-plunger 30, or other firing-member, is markedly uniform, thus providing a firearm having, to an outstanding degree, one of the qualities most desired by marksmen.

30 The invention may be carried out in other specific ways than that herein set forth without departing from the spirit and essential characteristics of the invention, and the present embodiment is therefore to be considered in all respects as illustrative and not restrictive, and all changes 35 coming within the meaning and equivalency range of the appended claims are intended to be embraced therein.

I claim:

1. A sear-mechanism for firearms, including in 40 combination: a spring-pressed firing-member; a sear serving to releasably hold the said firing-member in its cocked position; a trigger having a portion coacting with the said sear to releasably hold the same in position to restrain the said 45 firing-member; and spring-means urging the said sear into its firing-member-releasing position when the firearm is cocked, and also serving to move the said sear into position to release the said firing-member when the said trigger is operated.

50 2. A sear-mechanism for firearms, including in combination: a spring-pressed firing-member; a sear serving to releasably hold the said firing-member in its cocked position; a trigger having a portion coacting with the said sear to releasably 55 hold the same in position to restrain the said firing-member; spring-means urging the said sear into a position to hold the said firing-member in its cocked position; and a spring-pressed plunger 60 carried by the said sear and urging the said sear into its firing-member-releasing position when the firearm is cocked, and also serving to move the same into position to release the said firing-member when the said trigger is operated.

60 3. A sear-mechanism for firearms, including in combination: a spring-pressed firing-member; a

sear serving to releasably hold the said firing-member in its cocked position; a trigger having a portion coacting with the said sear to releasably hold the same in position to restrain the said firing-member; and spring-means carried by the 5 said sear and urging the said sear into its firing-member-releasing position when the firearm is cocked, and also serving to move the same into position to release the said firing-member when the said trigger is operated. 10

4. A sear-mechanism for firearms, including in combination: a spring-pressed firing-member; a sear serving to releasably hold the said firing-member in its cocked position; a trigger having a portion coacting with the said sear to releasably hold the same in position to restrain the said firing-member; spring-means urging the said sear into a position to hold the said firing-member in its cocked position; and second spring-means carried by the said sear and urging the said sear 15 into its firing-member-releasing position when the firearm is cocked, and also serving to move the same into position to release the said firing-member when the said trigger is operated. 20

5. A sear-mechanism for firearms, including in combination: a spring-pressed firing-member; a sear serving to releasably hold the said firing-member in its cocked position; a trigger having a portion coacting with the said sear to releasably hold the same in position to restrain the said firing-member; and a spring-pressed plunger urging the said sear into its firing-member-releasing position when the firearm is cocked, and also serving to move the said sear into position to release the said firing-member when the said trigger is operated. 30

6. A sear-mechanism for firearms, including in combination: a spring-pressed firing-member; a sear serving to releasably hold the said firing-member in its cocked position; a trigger having a portion coacting with the said sear to releasably hold the same in position to restrain the said firing-member; spring-means urging the said sear into a position to hold the said firing-member in its cocked position; and a spring-pressed plunger 45 carried by the said sear and urging the said sear into its firing-member-releasing position when the firearm is cocked, and also serving to move the same into position to release the said firing-member when the said trigger is operated. 50

7. In a bolt-action firearm, the combination with the bolt-unit thereof, of a spring-pressed firing-member; a sear serving to releasably hold the said firing-member in its cocked position; a trigger controlling the said sear; spring-means 55 urging the said sear into position to hold the said firing-member in its cocked position; and second spring-means constructed and arranged to be tensioned and relaxed by the movement of the said bolt-unit and serving when tensioned to move the said sear into position to release the said firing-member when the said trigger is operated.

8. In a bolt-action firearm, the combination with the bolt-unit thereof, of a spring-pressed 60 firing-member; a sear serving to releasably hold the said firing-member in its cocked position; a trigger controlling the said sear; spring-means urging the said sear into position to hold the said firing-member in its cocked position; and second spring-means constructed and arranged to be tensioned by the closing movement of the said bolt-unit and relaxed by the opening movement thereof and serving when so tensioned to move the said 70 75

sear into position to release the said firing-member when the said trigger is operated.

9. In a bolt-action firearm, the combination with the bolt-unit thereof, of a spring-pressed firing-member; a sear serving to releasably hold the said firing-member in its cocked position; a trigger controlling the said sear; spring-means urging the said sear in a position to hold the said firing-member in its cocked position; and second spring-means carried by the said sear and constructed and arranged to be tensioned to move the said sear into position to release the said firing-member when the said trigger is operated.

10. In a bolt-action firearm, the combination with the bolt-unit thereof, of a spring-pressed firing-member; a sear serving to releasably hold the said firing-member in its cocked position; a trigger controlling the said sear; spring-means urging the said sear in a position to hold the said firing-member in its cocked position; and second spring-means carried by the said sear and constructed and arranged to be tensioned by the closing movement of the said bolt-unit and relaxed by the opening movement thereof and serving when so tensioned to move the said sear into position to release the said firing-member when the said trigger is operated.

11. In a bolt-action firearm, the combination with the bolt-unit thereof, or a spring-pressed firing-member; a sear serving to releasably hold the said firing-member in its cocked position; a trigger controlling the said sear; spring-means urging the said sear in a position to hold the said firing-member in its cocked position; and a spring-pressed plunger carried by the said sear and constructed and arranged to be tensioned and relaxed by the movement of the bolt-unit and serving when tensioned to move the said sear into position to release the said firing-member when the said trigger is operated.

12. In an upturn-and-pullback firearm, the combination with a bolt-unit including a bolt-handle swinging transversely of the firearm; of a spring-pressed firing-member; a sear serving to releasably hold the said firing-member in its cocked position; a trigger coacting with the said sear; spring-means urging the said sear into position to hold the said firing-member in its cocked position; and second spring-means constructed and arranged to be tensioned and relaxed by the swinging movement of the said bolt-handle and serving when tensioned to move the said sear into position to release the said firing-member when the said trigger is operated.

13. In an upturn-and-pullback firearm, the combination with a bolt-unit including a bolt-handle swinging transversely of the firearm; of a spring-pressed firing-member; a sear serving to

releasably hold the said firing-member in its cocked position; a trigger coacting with the said sear; spring-means urging the said sear into position to hold the said firing-member in its cocked position; and second spring-means constructed and arranged to be tensioned by the bolt-locking movement of the said bolt-handle and relaxed by the unlocking movement thereof and serving when so tensioned to move the said sear into position to release the said firing-member when the said trigger is operated.

14. In an upturn-and-pullback firearm, the combination with a bolt-unit including a bolt-handle swinging transversely of the firearm; of a spring-pressed firing-member; a sear serving to releasably hold the said firing-member in its cocked position; a trigger coacting with the said sear; spring-means urging the said sear in a position to hold the said firing-member in its cocked position; and second spring-means carried by the said sear and constructed and arranged to be tensioned and relaxed by the swinging movement of the said bolt-handle and serving when tensioned to move the said sear into position to release the said firing-member when the said trigger is operated.

15. In an upturn-and-pullback firearm, the combination with a bolt-unit including a bolt-handle swinging transversely of the firearm; of a spring-pressed firing-member; a sear serving to releasably hold the said firing-member in its cocked position; a trigger coacting with the said sear; spring-means urging the said sear in a position to hold the said firing-member in its cocked position; and second spring-means carried by the said sear and constructed and arranged to be tensioned by the bolt-locking movement of the said bolt-handle and relaxed by the unlocking movement thereof and serving when so tensioned to move the said sear into position to release the said firing-member when the said trigger is operated.

16. In an upturn-and-pullback firearm, the combination with a bolt-unit including a bolt-handle swinging transversely of the arm; of a spring-pressed firing-member; a sear serving to releasably hold the said firing-member in its cocked position; a trigger coacting with the said sear; spring-means urging the said sear in a position to hold the said firing-member in its cocked position; and a spring-pressed plunger carried by the said sear and constructed and arranged to be tensioned and relaxed by the swinging movement of the said bolt-handle and serving when tensioned to move the said sear into position to release the said firing-member when the said trigger is operated.

ALBERT F. LAUDENSACK.
